UNITED STATES PATENT OFFICE.

ROWLAND T. WALES, OF SEWAREN, NEW JERSEY.

CORE-MOLD FOR HOLLOW WALLS.

1,272,736.

Specification of Letters Patent. Patented July 16, 1918.

Application filed August 26, 1916. Serial No. 117,008.

To all whom it may concern:

Be it known that I, ROWLAND T. WALES, a citizen of the United States of America, residing at Sewaren, in the county of Middlesex and State of New Jersey, have invented certain new and useful Improvements in Core-Molds for Hollow Walls, of which the following is a specification.

This invention provides an improved core mold for forming cavities in walls and other structures of concrete or similarly molded material. This application also includes certain features of core molds divided from my application No. 802,867, filed November 25, 1913, Patent No. 1,211,901.

Among the advantages of the core mold or core disclosed herein the following may be mentioned:—

1. When the surrounding concrete is hard this core may be easily collapsed and its parts easily disengaged and easily removed from the cavity formed by it.

2. It requires no upright taper to its form or parts and will form a cavity having walls parallel to each other and to the inclosing wall.

3. It will form a cavity which is uniformly very narrow compared with its width and height.

4. Its parts are few, simple and strong and are connected simply and securely.

5. Its parts are operated simply and easily without binding and will stand rough use without getting out of order.

Figures 1 and 2 show a core mold having side plates comprising wooden boards. Fig. 1 is a plan. The right of this view has a stronger design than its left, but is not so cheap. Fig. 2 is an elevation with the upper right corner of the view cut away sufficiently to show also a sectional view of part of the core on line 2—2 of Fig. 1. The lower right of the view is entirely broken away.

Figs. 3, 4 and 5 illustrate a side plate comprising a backing of corrugated sheet metal faced with a thin sheet of metal. These parts are used instead of the wooden boards shown in Figs. 1 and 2. Fig. 3 is a horizontal section on lines 3 of Figs. 4 and 5, and is broken away at the right of the view. Fig. 4 is a view of a lower corner looking toward Figs. 3 and 5 at the arrows marked 4. Fig. 5 is a vertical cross-section on lines marked 5 in Figs. 3 and 4.

Fig. 6 is similar to Fig. 3. It is a hori-

zontal cross-section and shows a design suitable for some work.

Figs. 1 and 2 show the parts of a core mold assembled as they are when the core is set or surrounded with concrete. The side plates are shown held apart by the spacers C. When the concrete is hard the core is collapsed and its parts removed from the cavity as follows: Remove the tie wire G. Cut the tie wires F with a long sharp bar which can be inserted downward within the core. Drive or force the spacers C out of alignment with each other, into positions illustrated by the dotted lines in the left of Fig. 1. If the spacers C start to slide in the direction in which they are forced, instead of turning and becoming disengaged, this will be stopped when they reach the button heads of E and the spacers can then be turned into positions similar to those shown by the dotted lines. All parts of the core will then be disengaged from each other and removable from the cavity formed in the concrete. Parts of the wires F will remain adhering to the concrete, but they are negligible.

In Figs. 1 and 2 each side plate comprises the wooden boards A, the extensions D or D' and the reinforcing straps Q or O, all bolted or screwed together as shown. The side plates are shown assembled in a pair with their largest exterior upright faces (forming opposite exterior faces of the core), parallel to each other. The narrow exterior upright face of a side plate (shown at the left of D and adjoining B in Figs. 1 and 2, or at the right of D' in Fig. 1), extends at an obtuse angle from the largest exterior upright face on the same side plate. This permits the side plate to be removed from the face of the completed cavity and without binding. At the ends of the boards A there is a recess from the inner upright surface of the side plate because the inner surface of the extension D or D' is disposed nearer to the largest exterior upright surface of the said plate. A spacer C is shown disposed in this recess and the inner surface of D or D' is shown bearing against the thin bearing edge of C. This recess gives ample room for C and thus allows C to have sufficient cross-section to be strong. C is preferably in the form of an angle iron, as shown. The recess permits the side plates to be disposed closer together.

than a distance equal to the width of the spacer measured perpendicularly to the faces of the side plates. This permits the side plates to have ample thickness for strength and enables the core to form a substantially narrow cavity in a wall. This is desirable in residences because the walls should be as narrow as possible. Wide cores would both weaken the walls and make it difficult to place reinforcement and concrete, because they would leave only a very narrow space between the cores and the mold plates of the wall. The substantially thin edge of the spacer C, against which D or D' bears, extends in an upright position as shown when the core is set. By a substantially thin edge I mean one that is substantially angular or sharp, or similar to the edge of the flange of an angle iron, or is not too blunt to cause an opposite edge or part of the spacer to move appreciably farther from D when the spacer is being turned on the said thin edge as an axis and into a position similar to that indicated by dotted lines near the left of Fig. 1. Two spacers are shown disposed in a pair with the bearing face of one adjoining that of the other. They have small holes for receiving the tie wires F and G, as shown. G is removed from view in Fig. 1. The spacers in a pair are shown disposed so that the upright edges of their adjoining bearing faces (the edges coinciding with the adjoining right angle corners of the spacers), are disposed in substantially the same plane with the thin bearing edges adjoining D. This permits the pair of spacers to be easily buckled out of engagement with each other before collapsing the core and without pressing toward each other sufficiently to be bound when the spacers start to turn on their thin edges as axes. The right angle corners of the spacers and therefore the coinciding edges of their bearing faces are shown disposed nearer to the center of the core than is any other edge of said bearing faces. This permits D or D' to bear against the spacers C at a line close to the ends of the plates A and thus subjects D or D' to a minimum possible bending strain. At the right of Figs. 1 and 2 is shown a stop H formed of any suitable material and inserted between a rigid part of the core and the spacers C. It is another suitable means for holding the spacers in position and preventing them from buckling out of engagement when the core is set. It is removed before collapsing the core. I are metal plates screwed to A. They each have a hole in which to insert some suitable hook or means for lifting the side plates from a completed cavity. The angular shaped splints B are shown covering the spaces between the upright edges of the side plates and overlapping them to a substantial distance each side of said space. The cen-

tral part of the inner surface of a splint does not overlap the side plates. This central part constitutes a part of the inner surface of the core. It is also at a slightly greater distance from the center of the core than the adjacent edges of the side plates because it has two inner faces meeting at an angle and each extending in a plane at an obtuse angle to the largest exterior face of the side plate adjoining the respective inner face of the splint. Room is thus given for the side plates to be easily moved toward each other without binding, when the cavity is completed and for their subsequent easy removal from the cavity. The ties F are shown holding the side plates, splints and spacers together. They also prevent the adjacent wings of two spacers from separating, because each tie F is shown bent into a small loop which passes in a reverse direction through small holes in said wings. The holes through D or D' for admitting the ties F are so small that they do not permit the leakage of an appreciable amount of cement into the core.

In Figs. 3, 4 and 5 is shown a modification of side plate comprising the parts D², L and M. Instead of the boards A shown in Figs. 1 and 2, the parts L and M are used. M is a facing of thin sheet metal. L is a backing of corrugated sheet metal. D² is an extension similar to D in Figs. 1 and 2, and is for the same object as D. D² is shown with slots cut in its edge, which appears in its right side in Fig. 4. The metal between these slots is shown fitted within the wide corrugations of L, as shown in Figs. 4 and 5. The short bolts N hold D², L and M together and permit renewing the facing M when M is worn out. Rivets or welding may be used instead of bolts. When two side plates like the one shown in Figs. 3, 4 and 5 are assembled together with spacers like C and splints like B, and in the manner illustrated by the side plates in Figs. 1 and 2, the corrugations of the backing L necessarily extend transversely of the direction of the lengths of said spacers C. The corrugations therefore act as ribs or beams extending in the same direction with the span of the side plates and thereby giving them strength. P is a flange bent inward at the bottom end of D² in Figs. 3, 4 and 5. A like flange P is also shown on the bottom of D³ in Fig. 6. Like flanges are also present (but not shown) on the bottom ends of D and D' in Figs. 1 and 2. They also act as ledges to prevent accidental falling of the spacers C into the lower part of a cavity when the core is being used at a higher position above the level of a completed part of a wall.

In Fig. 6 is shown a modification of side plate comprising a facing of thin sheet metal M, a backing of corrugated sheet

metal L', an extension D³ and the reinforcing strap Q, all fastened together by the bolts J, in the same manner as the parts A, D and Q at the left of Fig. 1. It is preferable that the bolts J conform to square holes for a slight depth under their heads, so that they will not be turned with their nuts when renewing M'.

What I claim is:—

- 10 1. A core mold for forming a cavity and comprising a pair of side plates, the largest molding face of one being parallel to the largest molding face of the other, a spacer for holding said plates apart and adapted 15 for disengagement while the core conforms in and with said cavity, and an angular shaped splint adapted to cover the space between upright edges of said side plates and to overlap them to a substantial distance 20 each side of said space, part of the inner surface of said splint constituting part of the inner surface of the core and extending in two planes each at an obtuse angle to the largest exterior face of one of said side 25 plates.
2. A core mold comprising a pair of side plates and a spacing member for holding them apart, each of said side plates having a sheet metal extension the inner surface of 30 which being disposed nearer to the exterior upright face of the side plate than to the largest inner upright face of the same said plate, and adapted to bear against the spacing member and thus maintain the last said 35 face at a shorter distance from the other side plate than a distance equal to the width of the spacing member measured in a direction substantially perpendicular to the planes of the said upright faces, and thus 40 adapting the core to form a substantially narrow cavity.
3. A core mold comprising a pair of side plates and a pair of spacers for holding them apart, each of said spacers having a 45 bearing edge adapted to prevent movement of one of said plates toward the other, said bearing edge being substantially thin and extending in an upright position when the core is set, the said spacer also having a bearing face which, when the core is set, 50 bears against the other spacer in said pair, and has an upright edge disposed in substantially the same plane which contains both the said thin edge and the like thin edge of the other spacer, and being disposed nearer to the center of the core than any other edge of said bearing face.
- 40
- 50
- 55

4. A core mold comprising a pair of side plates and a pair of spacers for holding them apart, each of said spacers having a bearing edge adapted to prevent movement of one of said plates toward the other, said bearing edge being substantially thin and extending in an upright position when the core is set, the said spacer also having a bearing face which, when the core is set, bears against the other spacer in said pair, 60 and has an upright edge disposed in substantially the same plane which contains both the said thin edge and the like thin edge of the other spacer, a flexible tie holding the spacers in position and passing 70 through said spacers.

5. A core mold comprising a pair of side plates and a pair of spacers for holding them apart, each of said spacers having a bearing edge adapted to prevent movement 75 of one of said plates toward the other, said bearing edge being substantially thin and extending in an upright position when the core is set, the said spacer also having a bearing face which, when the core is set, 80 bears against the other spacer in said pair, and has an upright edge disposed in substantially the same plane which contains both the said thin edge and the like thin edge of the other spacer, there being means 85 for holding said spacers in position.

6. A core mold comprising a pair of side plates and a pair of spacers for holding them apart, each of said spacers having a bearing edge adapted to prevent movement 90 of one of said plates toward the other, said bearing edge being substantially thin and extending in an upright position when the core is set, the said spacer also having a bearing face which, when the core is set, 95 bears against the other spacer in said pair, and has an upright edge disposed in substantially the same plane which contains both the said thin edge and the like thin edge of the other spacer, and being disposed nearer to the center of the core than any other edge of said bearing face.

In witness whereof, I have hereunto signed my name in the presence of two subscribing witnesses.
